UNITED STATES PATENT OFFICE.

AMBROSE WEBSTER WOODWARD, OF LANCASTER, PENNSYLVANIA.

BOTTLE WITH SPHERICAL OR BALL-VALVE STOPPER.

SPECIFICATION forming part of Letters Patent No. 724,405, dated March 31, 1903.

Application filed July 29, 1902. Serial No. 117,476. (No model.)

To all whom it may concern:

Be it known that I, AMBROSE WEBSTER WOODWARD, a citizen of the United States, residing at Lancaster, in the county of Lancaster and State of Pennsylvania, have invented 5 certain new and useful Improvements in Bottles with Spherical or Ball-Valve Stoppers; and I do hereby declare the following to be a full, clear, and exact description of the invention, such as will enable others skilled in the art to which it appertains to make and use the same.

This invention relates to improvements in a glass bottle with a glass stopper of that 15 class in which a ball-valve is mounted on the head of the bottle-neck to open and close the vent through said neck, permitting liquid to flow into or from said bottle and stoppering the same and in which provision is made to 20 securely lock said valve in either closed or opened positions.

The object of the invention is to provide a bottle and means for stoppering the same perfectly tight simple in construction, easily 25 operated, and indestructible as against the action of any liquid, acid or effervescent, confined therein, that will give no taint or disintegrated particle to deleteriously affect the aroma or flavor of said liquid or to adulterate 30 its mass.

The elements of the invention will severally and at large appear in the following description, and they will be separately or combinedly set forth or pointed out in the appended claims.

The purposes of the invention are attained by the mechanism, devices, and means illustrated in the accompanying drawings, with similar reference characters to designate like 40 parts throughout the several views, in which—

Figure 1 is a front elevation of the upper portion of a bottle-neck and stopper embodying the elements of the invention, showing 45 the valve in the position of closing or stoppering the bottle; Fig. 2, a view from the right, Fig. 1; Fig. 3, a sectional view of the portion to the left of the line $\alpha\alpha$ in Fig. 1; Fig. 4 an elevation similar to that in Fig. 1, 50 showing the valve in opened or unstoppeder position; Fig. 5, a view from the right of Fig. 4; Fig. 6, a sectional view of the portion

to the left of the line yy in Fig. 4; Fig. 7, a top view of Fig. 1; Fig. 8, a top of Fig. 5; Fig. 9, a top view of the bottle-neck with the 55 valve removed, showing the concaved spherical valve-seat; and Fig. 10, a straightened-out inner side view of the valve supporting and locking strip.

In the drawings, A designates the upper 60 portion of the neck of a bottle, which may be of any approved size and shape and preferably made of a good quality of glass; but the bottle is omitted in the drawings. The neck has at its upper end a head a of the required 65 depth and thickness, forming an offset or shoulder a' , surrounding the neck. In the under edge of this offset on opposite sides of the neck are formed notches or recesses a^2 of the required depth and length, with vertical 70 walls at diametrically opposite points and downwardly-sloping top walls forming inclined planes a^3 , disposed in one direction and vanishing in the under edge of said offset to be engaged by shoulders in the ears or 75 arms of the valve-supporting strip, yet to be described. In the top of the head a is formed a spherically-concaved recess a^4 of the required dimensions, ground in or smoothly finished to be spherically true, constituting the 80 seat of the ball-valve, yet to be described, while through its center opens the vent a^5 , leading from the bottle through the neck A.

The ball-valve B, also preferably made of a good quality of glass, is a spherical body, b, 85 of the required volume or mass, so that when its convex surface shall be ground off or otherwise smoothly finished it will be closely fitting to the concave surface of the recess a^4 when seated or rotated therein. Centrally 90 through the body b is an aperture or orifice b' to register with the vent a^5 in the bottle-neck when the valve is properly seated and rotated. On diametrically opposite sides, with their axes perpendicular to the axis of said 95 orifice, said body b is provided with trunnions b² b³ to be journaled in bearings through the ears or arms of a valve-supporting strip yet to be described, and midway between the extremities of the orifice b' and perpendicular 100 to its axis said body b is provided with a finger-grip b³, whereby it may be rotated to perform its functions, opening the passage-way into the bottle or closing the same, while at

the center of said finger-grip is a stop-lug b^4 to engage on the head of the bottle-neck to indicate that the orifice b' and the vent a^5 are in alinement, opening the bottle, and on 5 the opposite side of the grip, on one side of said orifice b' , is a stop-lug b^5 , also to engage on said head, indicating that said vent is closed or the bottle stoppered.

The valve-supporting strip C is an oblong 10 strap c of approved width and thickness, with a length to reach around the bottle-neck immediately underneath the offset a' and to be rotatably secured in place. To this end, near one extremity thereof, there is provided 15 an orifice c' to be engaged by a tongue or finger c^2 , projecting from the other extremity, which tongue or finger by passing through said orifice c' and being clenched home, as shown, forms a hook c^3 , securely holding the 20 strip in place, yet permitting rotation about said neck. At prescribed points on the strip, so as to be on opposite sides of the neck, are erected upwardly-projecting arms c^4 , which arms are made outwardly and inwardly curving 25 over the head a , so as to form offsets or shoulders c^5 to engage against the inclined planes a^3 , drawing the valve B down into the seat and to bring their upper ends or ears close to the sides of the body b when the 30 valve B is seated in place, while said ears are provided with bearing-orifices $c^6 c^6$, through which the trunnions $b^2 b^2$ of the valve are journaled, supporting said valve in operative position.

35 Now the several parts hereinbefore described and occupying the respective positions indicated in the drawings, an inspection thereof clearly shows, first, that the shoulders c^5 lying in the widest portions of the recesses a^2 40 the valve B lies practically loose in the recess a^4 , being freely rotatable therein; second, that rotating the valve B in the direction indicated by the arrow 1 till the lug b^4 contacts with the top of the head a will bring 45 the orifice b' into alinement with the vent a^5 , opening the passage-way into the bottle for the inflow or outflow of liquid thereto or therefrom; third, that turning the valve B in the direction indicated by the arrow 2 till 50 the lug b^5 contacts with the top of the head a will bring the orifice b' into a horizontal position and the body b over and across the vent a^5 , closing said vent or stoppering the bottle; fourth, that by horizontally rotating the valve 55 in the direction indicated by the arrow 3 will move the shoulders c^5 on the inclined planes a^3 toward the lower edge of the offset or shoulder a' , drawing the valve downwardly onto its seat, securely locking it, hermetically 60 closing the bottle when stoppered or holding it open when unstoppere, and, fifth, the strip C, lying below the head a , adjacent to its offset or shoulder a' , and by contacting therewith prevents said strip from slipping 65 upward and off.

It is well known that Patent No. 184,908, dated November 28, 1876, was granted to

William A. Root for a spherical bottle-stopper, and that Patent No. 206,271, dated July 23, 1878, was issued to Frederick J. Seybold 70 for a cam sphere or spheroidal bottle-stopper. No claim is therefore broadly made to the spherical stopper; but

What is considered new, and desired to be secured by Letters Patent, is—

75 1. A glass bottle having the neck, A, comprising the head, a , with the offset edge, a' , the recesses, a^2 , therein and having the inclined planes, a^3 , and the spherically-concaved valve-seat, a^4 , in the top of said head; a glass valve, B, having the spherical body, b , with the axial orifice, b' , the trunnions, b^2 , the finger-grip, b^3 , and the stop-lugs, b^4 and b^5 ; and the valve-supporting strip, C, having the oblong strap, c , with the end orifice, c' , 80 the end tongue, c^2 , forming the hook, c^3 , and having the upwardly-projecting arms, c^4 , with the outwardly and inwardly curving recesses forming the shoulders, c^5 , and the upper end ears with the trunnion-bearing orifices, c^6 , 85 all arranged, combined, and secured in position, substantially as described and for the purpose hereinbefore set forth.

90 2. In a bottle with a glass-ball stopper of the character described, the bottle-neck, A, having the head, a , with the offset edge, a' , the recesses, a^2 , therein and having the inclined planes, a^3 , and with the spherically-concaved valve-seat, a^4 , in the top of said head, substantially as described and for the purpose hereinbefore set forth.

95 3. In a bottle with a spherical glass stopper of the character described, the glass stopper, B, having the spherical body, b , with the axial orifice, b' , the trunnions, $b^2 b^2$, the finger-grip, b^3 , the stop-lug, b^4 , and the stop-lug, b^5 , substantially as described and for the purpose hereinbefore set forth.

100 4. In a glass bottle with a spherical glass stopper, both of the character described, the valve-supporting strip, C, composed of the strap, c , having the end orifice, c' , and the end finger, c^2 , forming the securing-hook, c^3 , and having the upwardly-projecting arms, c^4 , with the outwardly and inwardly curving 105 recesses forming the shoulders, c^5 , and the upper end ears with the trunnion-bearing orifices, $c^6 c^6$, substantially as described and for the purpose hereinbefore set forth.

110 5. The combination in a glass bottle, with the neck portion, A, having the head, a , with the under edge offset, a' , having the recesses, $a^2 a^2$, with the vertical end walls and the inclined planes, a^3 , and the spherically-concaved recess, a^4 , in the top of said head, of the glass stopper, B, having the spherical body, b , rotatably seated in said recess, a^4 , and having the axial orifice, b' , the trunnions, $b^2 b^2$, the finger-grip, b^3 , the central lug, b^4 , and the stop-lug, b^5 , with means provided to 115 rotatably support, and to securely lock said stopper, all substantially as described and for the purpose hereinbefore set forth.

120 6. The combination in a glass bottle, with

the neck portion, A, having the head, a , with the offset edge, a' , the recesses, a^2 , the inclined planes, a^3 , and the spherically-concaved recess, a^4 , and with the glass stopper, 5 B, having the spherical body, b , rotatably seated in said recess, a^4 , and having the axial orifice, b' , the trunnions, b^2 and b^3 , the finger-grip, b^3 , and the stop-lugs, b^4 and b^5 , of the valve-supporting strip, C, composed of the 10 neck-surrounding strap, c , with the end orifice, c' , and the end finger, c^2 , passing through said orifice, with the bent-over hook, c^3 , securing the strap in place, said strap having the upwardly-projecting arms, c^4 and c^5 , with

the outwardly and inwardly curving portions 15 forming the shoulders, c^5 and c^6 , and the upper end ears with the bearing-orifices, c^6 and c^6 , said shoulders seated in said recesses, a^2 , and engaging against said inclined planes, a^3 , and said bearing-orifices journaling said 20 trunnions, b^2 , all substantially as described and for the purpose hereinbefore set forth.

In testimony whereof I affix my signature in presence of two witnesses.

AMBROSE WEBSTER WOODWARD.
